UNITED STATES PATENT OFFICE.

FERDINAND E. KAUFFMANN, OF CLARK TOWNSHIP, UNION COUNTY, NEW JERSEY.

CLIPPING-MACHINE.

1,307,361.

Specification of Letters Patent. Patented June 24, 1919.

Application filed March 8, 1919. Serial No. 281,428.

To all whom it may concern:

Be it known that I, FERDINAND E. KAUFFMANN, a citizen of the United States, and a resident of Clark township, county of Union, and State of New Jersey, have invented certain new and useful Improvements in Clipping-Machines, of which the following is a specification.

This invention relates to an improved 10 clipping machine adapted for a number of purposes, but used largely in clipping velour articles, such as velour hats.

The device is portable, having a handle by means of which it is manipulated, and is 15 passed over the hat or other article and has a cutter which is usually driven by means of flexible shafting.

The present invention is designed to provide a clipping machine of this kind in 20 which the cutting is done more evenly than heretofore, the clipping machine can be used for a long time without dismantling to resharpen the cutting blades, and the stationary cutter against which the cutting 25 blades operate can be adjusted so that it presents a good edge to the cutting blades for a long time.

The invention further consists in improved disposition and construction of parts 30 more fully described hereinafter and also embodied in the claims.

In the drawing which illustrates one form of my improved clipping machine, Figure 1 is a side view of the machine with part of 35 the handle broken away to more fully disclose the construction. Fig. 2 is a top view of the machine shown in Fig. 1. Fig. 3 is a section of the front part of the machine on a plane indicated by line 3 in Fig. 2, and 40 Fig. 4 is a section of a bearing for the rotating cutter, taken on a plane indicated by line 4 in Fig. 3.

The body portion or frame of the machine comprises a frame or casing 10, which is 45 preferably box-like with side walls 11 and 12, a rear wall 13 and a curved front wall 14, which extends to the top of the casing to form a guard or shield for the rotary cutter of the machine and has a curved lower 50 portion 15 which terminates short of the bottom to permit the fur or hair that is to be trimmed to be engaged by the rotary cutter.

The rotary cutter is mounted on a shaft 16, which is adapted to have its projecting 55 end attached to a flexible shaft, and a bearing 17 receives the shaft and also has a

screw-threaded lug 18 to receive the casing of the flexible shaft.

The plug or bearing lug 19 is screwed into the wall 12 and projects materially from the 30 inner face to provide sufficient and adequate bearing for the cutter and its shaft. The lug is recessed, as at 20, to receive the end of the shaft 16, and the cutter has a sleeve 21 secured to the shaft 16 by suitable means, such 35 as a screw 22, which sleeve embraces the projecting part of the lug 19. The thin side wall of the casing would provide only a narrow bearing, but this structure provides a bearing of adequate length to keep the 40 parts alined. A suitable oil hole 23 permits lubrication. The sleeve 21 has lugs 24 properly spaced, and to these lugs are secured the blades 25, which are preferably formed 45 as parts of helices and have openings 26 in 50 rear of their cutting edges 27, the advantages of this construction being set forth 55 hereinafter.

The rotating cutter operates against a stationary cutter, and for this purpose I utilize the front end of the floor plate 28, the floor plate having a smooth bottom and being designed to slide along the surface of the goods being clipped. The floor plate is 60 adapted to be swung in a direction longitudinal to the casing and to be tilted transversely thereof. The floor plate has hubs 29 projecting into slots 30 in the side walls of the casing, and movable vertically therein and also adapted to have a limited rotation. 65 The slots 30 are extended part way into the inside of the side walls to form the recesses 31, and in these recesses are springs 32 which abut on the ends of the recesses 31 and on the hubs 29 to normally press the 70 hubs downward. Each hub has a recessed 75 part 33 with a rounded top portion 34, and stems 35 extend downward through the side walls, inside the springs 32 and have circular heads or balls 36 fitting in the recesses 80 and permitting a rocking of the floor plate 85 thereon as the cut away parts 37 permit such 90 partial rotation.

The stems are screw-threaded at their top 95 ends and the nuts 38 fit on the screw-threaded ends and bear on the top of the side walls of the casing. The stems are prevented from turning by any suitable means, such as flattening the stem and part of the hole through which it extends, as at 39. It 100 will be readily seen that by adjusting the nuts 38, the pivotal support, that is, the

line on which the floor plate swings, can be raised or lowered, and the floor plate can be tilted laterally of the casing to conform to any slight unevenness of the rotary cutter.

5 The floor plate has its front portion adapted to be removable, the form shown having a cutter or shearing plate 40 which is screwed or riveted into place and has its front edge disposed so that the cutter blades 10 of the rotary cutter shear against its edge and clip the fur. The plate 40 has its front edge turned upward and then slightly backward to present a sharp corner 41 as a shearing edge. When the edge becomes worn or 15 slightly flattened, the center on which the floor plate swings is lowered by the unscrewing of the nuts 38 and the front end of the floor plate is swung to a cutting position and a sharp corner is again presented for the 20 rotary cutter to operate against.

The machine is manipulated by means of a suitable handle, and in the form shown the handle is mounted on the rear of the casing. The rear of the casing has ears 42. Between 25 the ears fits the ear 43 of the handle 44, the handle being adjustable, in the preferred form swinging on the bolt 45 which passes through the ears, and is provided with a nut 46. The bolt is split, as at 47, and in 30 this split portion is arranged a locking screw 48, which spreads the split portion and locks the nut 46 into position, the screw 48 being tapered and the end of the split portion being slightly tapered and screw-threaded to 35 receive the screw 48.

The handle is preferably made of a frame 49 which has cheek-pieces 50 which inclose the chambered part 51 that is formed on the inside of the frame 49. The floor plate 28 40 has a central post 52 which is adapted to be used as a lever for swinging the floor plate longitudinally of the casing, and one form of attaching the actuating means is by providing the post 52 with a recessed portion 53, into which a ball 54 rests. The ball 54 is arranged on the end of a flexible stem, usually made of spring wire, although any other form of strand can be used, if desired, the strand or wire 55 passing back through 45 an opening 56 in the rear wall 13 of the casing, through a cut away portion 57 in the ear 43 of the handle, and it then passes through the chamber 51, and is provided with an end piece 58 which projects slightly 50 beyond the end of the handle, and to prevent its turning in the handle is preferably made square at one portion thereof, the square portion being rounded on its extremity and threaded to receive the nut 59. 55

60 It will thus be seen that by manipulating the nut 59, the strand or wire 55 can be gripped to pull back on the post 52 and swing the floor plate so that its front edge is raised. If the screw is loosened, the front 65 edge of the floor plate is caused to swing

downward, as the spring 60 exerts a pressure in opposition to the wire 55.

A suitable thumb piece 61 can be constructed over the top of the ears 42 to assist in guiding and holding the machine when 70 it is being operated. It will be evident that the adjustment of the floor plate is such that it can be tilted laterally of the frame, it can be rocked longitudinally of the frame, the centers on which it is moved are adjustable vertically, and the adjustment of the front or cutting edge of the floor plate with the rotary cutter is assured. 75

When the device is in operation, the handle is used to guide the machine so that 80 the floor plate glides along the fur to be clipped, and the fur is cut off by the contact of the blades of the rotary cutter with the front cutting edge of the floor plate. The recesses or open parts 26 in the cutter blades 85 permit the passage of air when the cutter is rotating at a high speed, so that the air is not forced by the cutter out through the opening between the end of the blade 15 and the front edge of the floor plate, and a 90 suction more than a pressure is instituted which assists the fur in being pulled up against the edge of the floor plate to be cut.

I claim:

1. A clipping machine comprising a box- 95 like casing, a floor plate, a vertically adjustable handle on the rear of the casing, a clipping mechanism on the front thereof, and means on the handle for swinging the floor plate.

2. A clipping machine comprising a box- like casing, a swinging floor plate, a vertically adjustable handle on the rear of the casing, a clipping mechanism at the front of the casing, an adjusting means for swinging 105 the floor plate, said means passing through the handle, and means at the end of the handle for manipulating the plate tilting means.

3. A clipping machine comprising a box- like casing, a floor plate, means for tilting 110 the floor plate laterally, means for swinging the floor plate longitudinally, and a rotary cutter placed to operate against the front edge of the plate.

4. A clipping machine comprising a box- like casing, a floor plate, means for tilting 115 the floor plate laterally, means for swinging the floor plate longitudinally, and a rotary cutter placed to operate against the front edge of the plate, said cutter comprising a sleeve and having blades cut away to leave an opening between the sleeve and the blade.

5. A clipping machine comprising a box- like casing, a rotary cutter at the front 120 thereof, a floor plate adapted to have its front edge coöperate with the rotary cutter, hubs on the floor plate, the sides of the casing having slots in which the hubs can slide, the hubs having cup-shaped recesses, rods with balls on their ends, said balls fitting in 125

130

the cup-shaped recesses, said rods extending up through the side walls of the casing, and means on the casing for adjusting the rods to tilt the floor plate laterally.

5. 6. A clipping machine comprising a box-like casing, a rotary cutter at the front thereof, a floor plate adapted to have its front edge coöperate with the rotary cutter, hubs on the floor plate, the sides of the casing having slots in which the hubs can slide, the hubs having cup-shaped recesses, rods with balls on their ends, said balls fitting in the cup-shaped recesses, said rods extending up through the side walls of the 10 casing, means on the casing for adjusting the rods to tilt the floor plate laterally, and springs acting in opposition to said adjusting means.

7. A clipping machine comprising a box-like casing, a rotating cutter in the front thereof, a floor plate mounted so as to swing longitudinally of the casing, the floor plate having a post with a round recess therein, a handle at the rear of the casing, a stem having a ball in the recess of the post and extending through the handle, and means on the handle for moving the stem.

8. A clipping machine comprising a box-like casing, a rotating cutter in the front thereof, a floor plate mounted so as to swing longitudinally of the casing, the floor plate having a post with a round recess therein, a vertically adjustable handle at the rear of the casing, a flexible stem passing through the handle and having a ball in the recess of the post, the end of the stem being threaded, a nut on the handle and engaging the threaded end of the stem, and a spring acting on the floor plate in opposition to the 40 stem.

9. A clipping machine comprising a frame, a rotary cutter in the frame, a floor plate, bearings on which the floor plate can swing, and means for varying the height of 45 the bearings in the frame.

10. A clipping machine comprising a frame, a rotary cutter in the frame, a floor plate, bearings on which the floor plate can swing, means for varying the height of the bearings in the frame, and means for swinging the floor plate and holding it in various 50 swung positions.

11. A clipping machine comprising a frame, a rotary cutter in the frame, a plate with a front cutting edge, a pivot on which 55 the plate swings to adjust its cutting edge to the cutter, and means for varying the height of the pivot relative to the cutter.

12. A clipping machine comprising a frame, a plug in one side wall thereof, the 60 plug being recessed, a cutter rotatably arranged in the frame, said cutter having a sleeve to embrace the plug, a shaft to which the sleeve is secured, the shaft having its end arranged in the recess of the plug, and 65 cutter blades arranged on the sleeve.

13. A clipping machine comprising a frame, a plug in one side wall thereof, the plug being recessed, a cutter rotatably arranged in the frame, said cutter having a 70 sleeve to embrace the plug, a shaft to which the sleeve is secured, the shaft having its end arranged in the recess of the plug, and cutter blades with openings in rear of their cutting edges, said blades being secured to 75 the periphery of the sleeve.

14. In a clipping machine, a casing having ears on its rear end, a handle fitting the ears, a bolt passing through the ears and the handle, the handle, the bolt and the casing 80 having substantially aligned openings, a floor plate adapted to rock, a flexible strand passing through the openings and attached to the floor plate, and means on the handle for operating the strand.

In testimony that I claim the foregoing, I have hereto set my hand, this 6th day of March, 1919.

FERDINAND E. KAUFFMANN.
